ELECTRIC RELAY DEVICE FOR INDICATING WEAK CURRENTS

Application filed November 12, 1924, Serial No. 749,573, and in Germany November 15, 1923.

Our invention relates to electric relay devices, and it has special relation to relays of the character described which may be actuated by extremely weak currents.

5 More particularly our invention contemplates the application of the well known phenomenon that an electric discharge or arc may be produced between two electrodes far more easily than usual if the gas between the 55
10 said electrodes is ionized. That is, an electric discharge between two electrodes, upon which a potential is impressed which is less than the normal potential necessary to cause an arc between said electrodes, may be initiated if the gas in the space between the 60
15 electrodes is brought to an ionized condition. By making use of this phenomenon, we have been able to indicate or utilize extremely weak currents, since only very small quantities of energy are necessary in order to produce the required ionization.

Some of the workers in this art, for instance Zehnder, (see "Annalen der Physik", Vol. 47, page 77 (1892); and Vol. 52, page 65
20 34 (1894)), have attempted to demonstrate the reception of Hertzian waves by producing an ionization between two spherical auxiliary electrodes, this ionization being effected by a low energy discharge produced 70
25 by Hertzian waves. The ionization thus produced served to start a luminous discharge between two primary or main electrodes. In the demonstration made by Zehnder, however, the auxiliary electrodes were connected 75
30 only with an oscillatory circuit, and it usually followed that in this oscillatory circuit, it was necessary to produce a potential which was substantially equal to the arcing potential of the auxiliary gas (this being about 80
35 200 volts) in order to initiate the luminous discharge between the main electrodes; this, of course, necessitated an appreciable amount of energy being used.

One of the main objects of our invention, 45 therefore, is to arrange an arc or discharge tube with one or several auxiliary electrodes whereby the same may be practically used to indicate weak currents. We markedly reduce the energy which is to be used to initiate the 50 arc or the discharge by applying an auxiliary

potential to the auxiliary gap, this auxiliary potential being so adjusted that a low additional potential on this gap is sufficient to exceed the discharge voltage of the auxiliary gap. By thus initiating the auxiliary discharge, the arc between the main electrodes is started and this eventuates a current strong enough to operate any device, for instance, a relay.

We may, on the other hand, so practice our 60 invention that the energy necessary for initiating the discharge may be still further reduced; that is, we may produce the ionizing auxiliary discharge between an auxiliary electrode and a main electrode, the latter being 65 preferably the cathode.

By practicing our invention in the above manner, and particularly by advantageously arranging the electrodes and the connections, we have succeeded in making a practicable 70 relay device which will operate with a very weak current. Other advantages will, of course, be apparent when the following specification is read in connection with the 75 accompanying drawing.

The accompanying drawing illustrates a number of embodiments of our invention, wherein:

Fig. 1 is a diagrammatic view of the circuits utilized when our invention is employed for receiving electric waves;

Fig. 2 illustrates the circuits as used when our invention is applied to a telegraph system; and

Fig. 3 illustrates the application of the invention for measuring purposes.

In Fig. 1 the auxiliary electrode 4 is arranged between the main electrodes 2 and 3 of the tube 1, it being noted that by this means the discharge potential of the auxiliary gap 3, 4 is markedly lower than that of the main gap 2, 3. The direct current potential impressed on the auxiliary gap 3, 4 is derived from a potentiometer consisting of a thermionic valve 10 and a resistance member 11. By suitably adjusting the resistance of the member 11 and the plate current of the tube 10, the voltage between the electrodes 3 and 4 is adjusted to be just below the discharge potential of the gap be- 95
100

tween said electrodes. The oscillatory circuit 9 acts upon the grid of the valve 10 and is connected in such a manner that when energized by an antenna (not shown in the drawing) it causes the current from the valve to diminish, this latter being equivalent to increasing the voltage between the cathode and the plate of the valve. Through such a voltage increase, the discharge potential of 10 the auxiliary gap 3, 4 is attained and the relay starts as above indicated.

Here again an extremely weak current may be detected by starting the arc between the main electrodes 2 and 3 and a device 7, such 15 for instance as a Morse recorder, will be actuated. A circuit breaker 12, as shown in the circuit, acts to open the main circuit. When the energy of the antenna ceases to act upon the oscillatory circuit 9 the main discharge 20 between electrodes 2 and 3 also ceases and is not started again until the voltage in circuit 9 is again built up. In this connection, it is to be noted that the latter circuits will give the desired results only when the circuit 25 breaker frequency is above that of the highest signal frequency. This application of our invention is especially useful in the reception of radiant energy.

Referring now to Fig. 2 our invention is 30 illustrated as being used with a telegraph system. In this figure, the main circuits whereby the electrodes 2 and 3 are energized, include a high resistance member 13 and a condenser 14 which shunt the tube 1, the 35 key 15 being connected to telegraph wires. The telegraph wire connected to the auxiliary electrode 4 is at substantially ground potential, and since the battery 6 is grounded at 19, a direct current voltage is impressed 40 upon the auxiliary gap 3, 4, which may be just below the discharge potential of said gap. Even if the telegraph wires have a very high resistance (that is 100000 ohms) the weak current, which passes upon the closing of the key 15, is sufficient to increase the 45 voltage of the auxiliary electrode 4, and said voltage attains the discharge potential of the auxiliary gap 3, 4. When the main discharge between the electrodes 2 and 3 is 50 thus started, the condenser 14 discharges through a telephone, diagrammatically represented at 16. Because of the high resistance, however, the discharge cannot be maintained and the arc fails to be re-started until 55 the condenser becomes re-charged up to a certain value of voltage. This latter character of interrupters is of considerable value if used in connection with the relay of our invention.

60 By thus applying our invention mechanical interrupting devices are not necessary. Moreover, through the proper arrangement and selection of the constants of the circuits, a sound may be observed in the telephone 16. 65 As before intimated, our invention is adapt-

ed not only to indicate weak currents, but, moreover, to measure the same.

In Figure 3, we have diagrammatically illustrated a circuit for effecting such measurement of weak currents. The arrangement is 70 very much like that of Fig. 2 with the addition that a condenser 17 is placed in the circuit of the auxiliary or initiating discharge electrode. A radio-active tube is represented at 18, that is a gas filled tube with two plate 75 electrodes, one of which is treated with a radio-active compound. Such a tube allows only an extremely weak current to pass. In Fig. 3 this current charges the condenser 17 until the potential of the auxiliary gap 3, 4 80 exceeds the discharge voltage thereof, whereupon a weak discharge passes said gap and serves to initiate a heavy discharge between the main electrodes 2 and 3. This latter arc, however, is automatically interrupted, as 85 above indicated. It is our experience that after the interruption of the discharge, the potential of the auxiliary electrode 4 remains at a value which is just below that normally required to cause a discharge to pass the auxiliary gap. Consequently a low additional charge on the condenser 17, caused by the extremely weak currents passing the radio-active tube 18, is sufficient to re-establish the 90 discharge potential of the auxiliary electrode 4 and the discharge phenomenon periodically repeats, the frequency of the same increasing as the ionization current from the tube 18 increases and this frequency again increasing if the capacity of the condenser 17 95 diminishes. As the frequency of the current pulsations becomes greater, the average intensity of the current in the main electrode circuit increases. Such an increase can be measured by a device 7 which may, for instance, comprise an integrating meter for 100 measuring such average values. As before pointed out, such measurement is only possible if at the moment of arcing the main electrodes have attained a sufficiently high potential. 105

It is necessary, therefore, in practicing our invention to choose the frequency of interrupting the main electrode circuit to thereby 110 secure a frequency higher than the arcing frequency. 115

While we have described several embodiments of our invention, it will be apparent that those skilled in the art may make many changes therein without departing from the 120 spirit and scope of the appended claims.

Having described our invention, what we claim as new and desire to secure by Letters Patent of the United States, is:

1. An electrical relay device for switching 125 considerable current by extremely weak current, comprising a gas discharge tube, solid main electrodes and an auxiliary electrode situated therein, said main electrodes being connected to a source of controlled energy sup- 130

ply of too low a value normally to produce ionization and start a discharge means for imposing an auxiliary potential upon said auxiliary electrode, further means for imposing controlling potential upon said auxiliary electrodes, said auxiliary potential being of such value that upon the imposition of a low controlling potential the tube becomes ionized and a low voltage arc discharge is started between said main electrodes.

2. An arc electrical relay device for switching considerable current by extremely weak current, comprising a gas discharge tube, solid cathode and anode electrodes situated therein, an auxiliary electrode between said main electrodes and influencing their electric field, said main electrodes being connected to a source of energy supply of too low a value normally to produce ionization and start a discharge therebetween means for imposing an auxiliary potential upon said auxiliary electrode further means for imposing controlling potential upon said auxiliary electrodes, said auxiliary potential being of such value that upon the imposition of a low additional controlling potential the tube becomes ionized and a low voltage arc discharge occurs between said auxiliary electrode and the cathode, thus initiating the discharge between said main electrodes.

3. An electrical relay device for switching considerable current by extremely weak current, comprising a gas discharge tube, solid main electrodes therein, an auxiliary electrode situated between said main electrodes and adapted to influence the electric field therebetween, said main electrodes being connected to a source of energy supply of too low a value normally to produce ionization and start a discharge therebetween, means for imposing a biasing potential upon said auxiliary electrode, means for imposing a further low controlling potential upon said auxiliary electrode for initiating a low voltage discharge between said main electrodes by ionizing the space between the auxiliary electrode and one of the main electrodes, and an interrupter device in the circuit of said main electrodes, said interrupter being actuated by the discharge current between said main electrodes.

4. An electrical relay device for switching considerable current by extremely weak current, comprising a gas discharge tube, solid main electrodes therein, an auxiliary electrode situated between said main electrodes, said main electrodes being connected to a source of energy supply of too low a value normally to produce ionization and start a discharge therebetween, means for imposing a biasing potential upon said auxiliary electrode, means for imposing a further low controlling potential upon said auxiliary electrode for initiating a low voltage discharge between said main electrodes by ionizing the

space between the auxiliary electrode and one of the main electrodes, and an automatically recurring interrupting device connected in the circuit of said electrodes.

5. In an electric relay for switching considerable current by extremely weak current, a vessel filled with a gaseous atmosphere, two solid main electrodes disposed therein to form a discharge gap, an auxiliary electrode to form an auxiliary gap together with one of said electrodes, said main electrodes being connected to a source of energy supply of too low a value normally to ionize said gap and start a discharge therebetween, means for imposing an auxiliary potential upon said auxiliary electrode, further means for imposing a controlling potential upon said auxiliary electrode, said auxiliary potential being of such value that upon the further imposition of a low additional controlling potential, said auxiliary gap becomes ionized and a low voltage arc discharge is produced between said main electrodes.

6. In an electric relay for switching considerable current by extremely weak current, comprising a vessel filled with a gaseous atmosphere, main solid and fixed electrodes situated therein to form a discharge gap, an auxiliary electrode arranged intermediate said main electrodes to form an auxiliary discharge gap with one of said main electrodes, said main electrodes being connected to a source of controlled energy supply of too low a value normally to ionize said gap and start a discharge therebetween means for imposing a biasing potential upon said auxiliary electrode, means for imposing further controlling potential upon said auxiliary electrode, said biasing potential being of such value that upon imposition of an extremely weak controlling potential upon said auxiliary electrode said auxiliary discharge gap becomes ionized, initiating the discharge between said main electrodes.

7. In an electric relay device for switching considerable current by extremely weak current, comprising a glass tube filled with a gaseous atmosphere, solid and fixed cathode and anode electrodes situated within said tube to form a discharge gap, an auxiliary electrode within said tube arranged intermediate said cathode and said anode to form an auxiliary discharge space together with said cathode, said cathode and anode being connected to a source of controlled energy supply of too low a value normally to ionize said gap and produce a discharge therebetween, means for imposing biasing potential upon said auxiliary electrode, means for imposing further controlling potential upon said auxiliary electrode, said biasing potential being of such value that, upon the further imposition of an extremely weak controlling potential upon said auxiliary electrode, an ionizing discharge of said auxiliary space is start-

ed initiating the main discharge between said cathode and said anode.

8. In an electric relay system for switching considerable current by extremely weak current, comprising an input circuit carrying weak controlling currents and an output circuit carrying heavy controlled currents, a gas tube including solid main electrodes inserted in said output circuit, a source of potential in said output circuit of too low a value normally to produce ionization and start a discharge between said main electrodes of said tube, an auxiliary electrode within said tube connected to said input circuit, means to impose a biasing potential upon said auxiliary electrode, further means for imposing controlling potential upon said auxiliary electrode, said biasing potential being of such value that, upon the further imposition of an extremely low additional controlling potential derived from said input currents, said gap becomes ionized and a low voltage arc discharge is produced between said main electrodes.

25 9. In an electric relay system for switching considerable current by extremely weak current, comprising an input circuit carrying weak controlling currents, an output circuit to carry heavy controlled currents, a discharge tube filled with a gaseous atmosphere and including solid anode and cathode electrodes inserted in said output circuit, a source of operating potential connected in said output circuit of too low a value normally to produce ionization and start a discharge between said cathode and said anode, an auxiliary electrode arranged intermediate said cathode and said anode and connected to said input circuit to form an auxiliary discharge path means for imposing a biasing potential upon said auxiliary electrode, further means for imposing a controlling potential upon said auxiliary electrode, said biasing potential being of such value that, upon the further imposition of an extremely low additional controlling potential derived from said controlling currents in said input circuit, an ionizing discharge is produced within said auxiliary discharge gap initiating the main discharge between said cathode and said anode.

10. In an electrical system comprising an input circuit carrying weak controlling currents, an output circuit to carry heavy controlled currents, a discharge tube filled with a gaseous atmosphere, including solid main electrodes, a source of operating potential inserted in said output circuit of too low a value normally to produce ionization and start a discharge between said main electrodes, an auxiliary electrode connected to said input circuit to form an auxiliary discharge gap with one of said main electrodes, means for imposing biasing potential upon said auxiliary electrode, further means for

imposing a controlling potential upon said auxiliary electrode, said biasing potential being of such a value that, upon the further imposition of an extremely low additional controlling potential derived from said controlling currents in said input circuit, an ionizing discharge occurs at said auxiliary gap initiating the discharge between said main electrodes and a high ohmic resistance inserted in said output circuit in series with said main electrodes.

11. In an electrical system comprising an input circuit carrying weak controlling currents, an output circuit to carry heavy controlled currents, a discharge tube filled with a gaseous atmosphere including solid main electrodes, a source of operating potential inserted in said output circuit of too low a value normally to produce ionization and start a discharge between said main electrodes, an auxiliary electrode connected to said input circuit to form an auxiliary discharge gap with one of said main electrodes, means for imposing a biasing potential upon said auxiliary electrode, further means for imposing a controlling potential upon said auxiliary electrode, said biasing potential being of such a value that, upon the further imposition of an extremely low additional controlling potential, an ionizing discharge occurs at said auxiliary gap initiating the discharge between said main electrodes, a high ohmic resistance in series with said electrodes and a condenser connected in parallel to said main electrodes.

12. In an electric system comprising an input circuit carrying weak controlling currents, an output circuit to carry heavy controlled currents, a discharge tube filled with a gaseous atmosphere including solid main electrodes, a source of potential inserted in said output circuit of too low a value normally to produce ionization and start a discharge between said main electrodes, an auxiliary electrode connected to said input circuit to form an auxiliary discharge gap with one of said main electrodes, means for imposing a biasing potential upon said auxiliary electrode, further means for imposing a controlling potential upon said auxiliary electrode, said biasing potential being of such a value that, upon the further imposition of an extremely low additional controlling potential, an ionizing discharge occurs of said auxiliary gap initiating the discharge between said main electrodes and an interrupting device in said output circuit automatically opening said output circuit upon closing of the output current by the discharge of said main electrodes.

13. A system for detecting extremely weak currents comprising in combination a discharge relay consisting of a tube filled with a gaseous atmosphere and having a pair of main electrodes situated therein, an auxil-

- 5 iary electrode arranged intermediate said main electrodes, a source of electric energy supply connected to said main electrodes in series with a high ohmic resistance and being of too low a value to normally start a discharge between said main electrodes, a condenser connected between said main electrodes, a further condenser connected between one of said main electrodes and said auxiliary electrode and further means to apply potential variations derived from the currents to be detected to said auxiliary electrode and the remaining one of said main electrodes and a current translating device arranged in the output circuit connected to said main electrodes.
- 10 14. In a system for detecting extremely weak electric currents comprising in combination a discharge relay consisting of a tube filled with a gaseous atmosphere and having a cathode and anode electrode situated therein, an auxiliary electrode arranged intermediate said cathode and said anode electrode, a source of energy supply connected to said cathode and said anode in series with a high ohmic resistance, a variable condenser connected in parallel to said cathode and said anode, a further variable condenser connected in parallel to said auxiliary electrode and said cathode and a device carrying weak currents to be detected connected between said auxiliary electrode and said anode and a current translating device in the output circuit connected to said cathode and said anode.
- 15 15. In an electrical relay device comprising a vessel filled with a uniform gaseous atmosphere, solid main electrodes within said vessel, an auxiliary electrode within said vessel, sources of operating potential and biasing potential for said main electrodes and for said auxiliary electrode, respectively, further means for applying controlling potential upon said auxiliary electrode said operating and biasing potentials being of such value that normally substantially no ionization is produced of said atmosphere, and said biasing potential being further of such value, that with the imposition of a low additional controlling potential ionization is started and a low voltage arc discharge is initiated between said main electrodes.
- 20 16. In an electrical system comprising an input circuit carrying weak controlling currents; an output circuit to carry heavy controlled currents; a gaseous discharge tube including solid main electrodes inserted in said output circuit; an auxiliary electrode within said device connected to said input circuit; sources of operating potential and biasing potential for said main electrodes and said auxiliary electrode, respectively; further means for applying controlling potential upon said auxiliary electrode, said operating and biasing potentials being of such value that normally substantially no ionization is produced within said tube and said biasing potential being further of such value that with the imposition of a low additional controlling potential ionization is started and a low voltage arc discharge initiated between said main electrodes; an electric reactance associated with said input circuit and connected to said auxiliary electrode to be electrically charged by the controlling currents in said input circuit to produce controlling potential upon said auxiliary electrode for initiating a discharge between said main electrodes.
- 25 17. In an electrical system comprising an input circuit carrying weak controlling currents; an output circuit to carry heavy controlled currents; a discharge device consisting of a vessel filled with a uniform gaseous atmosphere; a pair of solid main electrodes situated within said vessel and connected in said output circuit; an auxiliary electrode within said vessel; sources of operating potential and biasing potential for said main electrodes and said auxiliary electrode, respectively; said input circuit being connected between said auxiliary electrode and one of said main electrodes; and an electrical condenser connected between said auxiliary electrode and the remaining one of said main electrodes to be charged by the controlling currents in said input circuit for producing controlling potential upon said auxiliary electrode to initiate the electric discharge between said main electrodes.
- 30 18. In an electrical system comprising an input circuit carrying weak controlling currents; an output circuit to carry heavy controlled currents; an electrical discharge device filled with a gaseous atmosphere; main electrodes situated within said device and connected in said output circuit; potential means in said output circuit for alternately starting and stopping the electric discharge in said device; an auxiliary electrode within said device; said input circuit being connected to said auxiliary electrode; and an electric reactance connected to said auxiliary electrode and to said input circuit to be charged by the controlling currents in said input circuit for producing input potential upon said auxiliary electrode for controlling the electrical discharge of said device.
